PROCESS FOR OXIDATION OF SECONDARY ESTERS OF PHOSPHOROUS ACID TO PRIMARY AND SECONDARY ESTERS OF PHOSPHORIC ACID

Charles F. Baranauckas, Niagara Falls, and James J. Hodan, Tonawanda, N.Y., assignors to Hooker Chemical Corporation, Niagara Falls, N.Y., a corporation of New York
No Drawing. Filed Aug. 16, 1963, Ser. No. 302,705
15 Claims. (Cl. 260—985)

This invention relates to the preparation of esters of phosphoric acid. More particularly, it relates to the oxidation of secondary esters of phosphorous acid in the presence of a catalyst to form the corresponding primary and secondary esters of phosphoric acid.

Secondary esters of phosphorous acid have the general formula

(1)

wherein R may be aliphatic or aromatic. It is known in the art that secondary esters of phosphorous acid (secondary phosphites) are not amenable to oxidation. Kosolapoff, on page 194 of the text, "Organic Phosphorus Compounds," published by Wiley and Sons (1958), states that the secondary esters of phosphorous acid exist substantially in the ketone form. To support the pentavalent ketone formula of these esters, illustrated in Formula 1, their lack of oxidizability, true acidic characteristics, inability to add cuprous halides, and other physical properties are cited. Thus, this structure has been adopted as the true form of secondary esters of phosphorous acid.

It has been found that the diesters of phosphorous acid may be oxidized, in the presence of a catalyst, to the mono- and diesters of phosphoric acid. Monoesters and diesters of phosphoric acid have the formulae:

(2)

and

(3)

respectively, wherein R is as defined above.

In accordance with this invention, it has been found that mono- and diesters of phosphoric acid and mixtures thereof may be prepared by passing a gas containing oxygen through a reaction mixture of a diester of phosphorous acid having the formula

where R is selected from the group consisting of alkyl, alkenyl, phenyl, alkylphenyl, halo-substituted aryl, halo-substituted alkyl, halo-substituted alkenyl, alicyclic, aralkyl and mixtures thereof, and a catalyst.

The process of this invention may be carried out in the presence of a metal or a metal oxide. Examples of the elements which may be utilized in the practice of this invention are copper, copper oxides and metals selected from the transition elements such as scandium, titanium, vanadium, chromium, manganese, iron, cobalt, nickel, yttrium, zirconium, niobium, molybdenum, technetium, ruthenium, rhodium, palladium, rhenium, tungsten, osmium, iridium, platinum, their oxides, and mixtures thereof.

Suitable dialkyl, halo-substituted dialkyl and dialicyclic phosphites which may be utilized in the present invention may contain from 1 to about 20 carbon atoms in each alkyl, with the more preferred phosphites containing from 1 to about 12 carbon atoms and the most preferred phosphites containing from 1 to about 6 carbon atoms in each alkyl. Preferably, the alicyclic radical has from 4 to 8 carbon atoms. Examples of these phosphites are dimethyl phosphite, diethyl phosphite, dipropyl phosphite, diisopropyl phosphite, dibutyl phosphite, di-tertiary butyl phosphite, dihexyl phosphite, diisohexyl phosphite, diheptyl phosphite, dinonyl phosphite, dicyclohexyl phosphite, didecyl phosphites, didodecyl phosphite, distearyl phosphite, di-2-chloroethyl phosphite, di-3-bromopropyl phosphite, di-4-chloroethyl phosphite, dicyclohexane phosphite, di(3-ethylcyclopentane)phosphite, di(1,3-cyclopentadiene)phosphite, methyl ethyl phosphite, methyl propyl phosphite, methyl hexyl phosphite, 3-bromopropyl methyl phosphite, ethyl butyl phosphite, hexyl decyl phosphite, and the isomers thereof.

Suitable dialkenyl and halosubstituted dialkenyl phosphites which may be utilized in the practice of this invention may contain from 2 to about 10 carbon atoms in each alkylene, with from 2 to about 8 carbon atoms being more preferred and the most preferred phosphites containing from 1 to about 6 carbon atoms. Illustrative of these phosphites are di-(2-bromo-2-butene) phosphite, di-(3-chloro-4-heptene) phosphite, di-4-heptene phosphite, diallyl phosphite, dimethylallyl phosphite, allyl methylallyl phosphite, 2-chloro-2-butene heptene phosphite and di(3-heptene) phosphite, and so forth.

Diaryl, halosubstituted diaryl and diaralkyl phosphites which may be utilized in the practice of this invention are diphenyl phosphite, dibenzyl phosphite, dicesyl phosphite, di(2-decylphenyl) phosphite, di(2-dodecylphenyl) phosphite, di-(2-chlorophenyl) phosphite, di-(2-bromophenyl) phosphite, di-(2,6-dichlorophenyl) phosphite, di-(2,4-dibromophenyl) phosphite, di-(2-iodophenyl) phosphite, phenyl cresyl phosphite, 2-chlorophenyl cresyl phosphite, and so forth. The aryl, halo-substituted aryl, and aralkyl may contain from 6 to about 18 carbon atoms, it being preferred to utilize aryl groups having from 6 to about 10 carbon atoms, with the most preferred embodiment of this invention having the aryl, halo-substituted aryl, and aralkyl containing from 6 to 8 carbon atoms.

In carrying out the process of this invention the phosphite and a sufficient amount of a catalyst are added to a reaction vessel. Oxygen or oxygen contained in a carrier gas, e.g., nitrogen, air, and so forth, is passed through the reaction mixture. A stoichiometric or excess amount of oxygen may be utilized. The excess of oxygen or air utilized may be more than 200 times the stoichiometric amount required to perform the reaction of the invention. Usually, however, one utilizes an excess of oxygen between about 1 and 200 times the stoichiometric amount required, with about 1 to 30 times being preferred and 1 to 15 times being most preferred. When oxygen is in a carrier gas it is preferred to utilize a mixture in the range of about 10-40 percent oxygen and about 90-60 percent carrier gas.

The amount of catalyst employed in the process of this invention may be between about 0.0001 and 1 mole per mole of secondary phosphite utilized, with between about 0.001 mole and 0.5 mole per mole of phosphite being preferred with between about 0.001 and 0.1 mole of catalyst per mole of phosphite utilized being the most preferred. Usually, a gram weight of from about 0.005 gram and 5 grams of catalyst per molar weight of phosphite may be employed.

The reaction may be carried out at a temperature from about 65 to 300 degrees centigrade, it being more

preferred to carry out this process by maintaining a temperature from about 100 to 200 degrees centigrade with the most preferred temperature being maintained at between 100 and 160 degrees centigrade. It is to be understood that atmospheric, sub-atmospheric, and superatmospheric conditions may be utilized in the practice of this invention depending on the conditions desired. It is also within the scope of this invention that this process may be carried out in a continuous manner.

Mono- and diesters of phosphoric acid may also be prepared following the above description by passing oxy-

ing the invention except as defined in the appended claims. All temperatures are in degrees centigrade and all parts are by weight, unless otherwise set forth.

Examples 1-6

In these examples a copper oxide catalyst was employed. The secondary phosphite, as set forth in Table I, and catalyst were placed in the reaction vessel in the amounts indicated. Oxygen was then passed into the reaction vessel below the level of the mixture for a period of time as indicated in the table.

TABLE I

Secondary Phosphites		Oxygen (moles/hour)	Cupric Oxide Catalyst (parts)	Reaction time (hours)	Reaction Temperature	Product Analyses	
Type	Moles utilized					Percent $(RO)_2P(O)(OH)$	Percent $RO_2P(O)(OH)_2$
Methyl-----	2.0	0.21	5.0	18.5	115-120	55.0	29.0
Ethyl-----	4.0	0.50	10.0	20	110-120	48.5	23.8
Butyl-----	1.0	0.21	5.0	10.25	115-120	17.9	46.6
Hexyl-----	0.5	0.25	5.0	2.0	115-125	1.9	46.2
Phenyl-----	1.0	0.21	5.0	8.25	115-120	-----	3.7
Ethyl-----	0.5	0.21	0	8.0	100-110	-----	-----

gen or a gas containing oxygen through a reaction mixture comprising white or yellow phosphorus, a hydroxyl containing compound having the formula

wherein R^2 is selected from the group consisting of phenyl, alkylphenyl, halo-substituted phenyl, alkyl, halo-substituted alkyl, alkenyl, halo-substituted alkenyl, aralkyl and alicyclic in the presence of a catalyst selected from the group consisting of aluminum, copper, scandium, titanium, vanadium, chromium, manganese, iron, cobalt, nickel, yttrium, zirconium, niobium, molybdenum, technetium, ruthenium, rhodium, palladium, rhenium, tungsten, osmium, iridium, platinum, their oxides, and mixtures thereof. The described hydroxyl-containing compound is employed in place of the secondary ester of phosphorous acid. Illustrative of hydroxyl containing compounds which may be utilized are methanol, ethanol, propanol, 2-propanol, butanol, heptanol, decanol, dodecanol, stearyl alcohol, 2-chloropropanol, 3-bromobutanol, propanol, tert-butanol, phenol, cresyl alcohol, diresyl alcohol, cyclohexanol, 1,3-dimethyl-4-cyclohexanol, benzyl alcohol, neopentyl alcohol, 2-phenyl-ethanol, and so forth. It is preferred that the alkyl and halo-substituted alkyl contain from 1 to about 20 carbon atoms, with the preferred alkyl and halo-substituted alkyl having 1 to about 12, and the most preferred alkyl and halo-substituted alkyls having from 1 to about 6 carbon atoms. The preferred alkenyl and halo-substituted alkenyl may contain from 2 to about 10 carbon atoms, with the more preferred alkylene and halo-substituted alkylene containing from 2 to about 8 carbon atoms and the most preferred alkenyl and halo-substituted alkenyl containing from 2 to 6 carbon atoms. Further, it is preferred that the substituted phenyl, halo-substituted phenyl, and aralkyl contain from 6 to about 18 carbon atoms, with the more preferred substituted phenyl, halo-substituted phenyl, and aralkyl containing from 6 to about 10 carbon atoms, the most preferred substituted phenyl, halo-substituted phenyls and aralkyl containing from 6 to about 8 carbon atoms, and the preferred alicyclic containing 4 to 6 carbon atoms. The hydroxyl containing compound may have a primary, secondary or tertiary hydroxyl. The ratio of alcohol of phosphorus may be from 1:1 to about 10:1 with the preferred ratio being from 1:1 to about 8:1 and the most preferred ratio being from 1:1 to 5:1. It is theorized that the primary and secondary esters of phosphoric acid are formed in this reaction by the oxidation of a secondary ester of phosphorous acid which may be formed as an intermediate for a brief period of time.

The following examples illustrate the process of the invention, however, they are not to be construed as limit-

25 The mixture of the dialkyl phosphate and the monoalkyl phosphate may be separated by known techniques if desired, such as by forming their salts which have different solubilities and then fractionally crystallizing or dissolving, or by chromatographic separation. Analysis of the unseparated residue was carried out with a Sargent Auto Titrator. The products peaked in different areas against a caustic standard to establish the percentage of primary and secondary phosphate present in the product.

30 Use of scandium, titanium, vanadium, cobalt, yttrium, niobium, technetium, ruthenium, rhodium, rhenium, osmium and iridium, and the oxides of the various metals mentioned earlier will be equivalent to using the metals listed above in this example. Example 6 above (no catalyst) was utilized as a control and establishes that no dialkyl acid phosphate was formed, elements in the first transition series being more preferred.

35 Instead of the phosphites indicated, di-tertiary butyl phosphite, diisooctyl phosphite, distearyl phosphite, di-cyclohexyl phosphite, di-3-bromopropyl phosphite, di-4-chlorododecyl phosphite, ethyl butyl phosphite, hexyl decyl phosphite, di(2-bromo-2-butene) phosphite, di-4-heptene phosphite, di(2-chlorophenyl) phosphite, dibenzyl phosphite, dicyclohexyl phosphite and diresyl phosphite, used in the processes of Example 2 results in the corresponding primary and secondary esters of phosphoric acid.

40 50 *Example 7*

55 Diethyl phosphite (138 parts) and vanadium pentoxide (0.5 part) were placed in a reaction vessel and heated to about 115 degrees centigrade. Oxygen was passed below the level of the reaction mixture for about 10 hours at 187 milliliters per hour. The initial exothermic reaction was cooled and the temperature was maintained about between 130 degrees and 160 degrees centigrade. Analysis indicated that 56.2 percent of the product was diethyl acid phosphate,

60 65 and 31.9 percent of the product was monoethyl acid phosphate,

Example 8

70 75 Example 7 was repeated utilizing diethyl phosphite (138 parts) and cobalt trioxide (0.5 part). The product analyzed 5.9 percent diethyl phosphate,

and 38.7 percent of monethyl phosphate

Example 9

Example 7 was repeated utilizing titanium dioxide as a catalyst. The reaction was run for about 12 hours. Analysis showed that 9 percent of the residue recovered was diethyl phosphate

and 5.7 percent of the residue was monoethyl phosphate

Examples 10-17

Phosphorus, hydroxyl containing compound and appropriate catalyst in the proportions set forth in Table II were heated with stirring to the desired temperature. Oxygen or air was then added under the surface of the reaction mixture for a period of time as indicated in the aforementioned Table II. The exothermic reaction was maintained within the desired temperature range by known cooling means. The reaction mixture was titrated at intervals with standard iodine for secondary phosphite. After the phosphite content was less than three percent, as determined by titration with standard iodine, the excess hydroxyl containing compound was distilled off. In lieu of cuprous oxide utilized in the examples, it is also within the scope of this invention that if elements of the first, second and third transition series are employed they will give similar results, elements in the first transition series being the more preferred catalyst to be employed in this invention.

wherein R is as described above, and a catalyst selected from the group consisting of copper, copper oxides, transition elements and their oxides.

2. A process in accordance with claim 1 wherein the catalyst is selected from the group consisting of copper, scandium, titanium, vanadium, chromium, manganese, iron, cobalt, nickel, yttrium, zirconium, niobium, molybdenum, technetium, ruthenium, rhodium, palladium, rhenium, tungsten, osmium, iridium, platinum, their oxides, and mixtures thereof.

3. A process in accordance with claim 1 wherein the catalyst is copper.

4. A process in accordance with claim 1 wherein the catalyst is vanadium pentoxide.

5. A process in accordance with claim 1 wherein the catalyst is cuprous oxide.

6. A process in accordance with claim 1 wherein the catalyst is cobalt trioxide.

7. A process in accordance with claim 1 wherein the catalyst is titanium dioxide.

8. A process for the preparation of secondary esters of phosphoric acid

wherein R is selected from the group consisting of alkyl, alkenyl, phenyl, alkylphenyl, halo-substituted phenyl and alkylphenyl, halo-substituted alkyl, halo-substituted alkenyl, alicyclic of 4 to 8 carbon atoms, and phenylalkyl comprising passing oxygen through a reaction mixture of phosphorus, a hydroxyl containing compound of the formula R^2OH , wherein R^2 is selected from the group consisting of phenyl, alkylphenyl, halo-substituted phenyl,

*Air was utilized.

While the invention has been set forth in relation to the specific examples above, it should be realized that the invention in its broadest aspects is not so limited. Other modifications thereof will become apparent to one skilled in the art upon a reading of this disclosure. Such modifications are considered to be within the scope of this invention.

What is claimed is:

1. A process for the preparation of secondary esters of phosphoric acid having the formula:

wherein R is selected from the group consisting of alkyl, alkenyl, phenyl, alkylphenyl, halo-substituted phenyl and alkylphenyl, halo-substituted alkyl, halo-substituted alkenyl, alicyclic of 4 to 8 carbon atoms, and phenylalkyl comprising passing oxygen through a reaction mixture of a diester of phosphorous acid of the formula:

alkyl, halo-substituted alkyl, alkenyl, halo-substituted alkenyl, phenylalkyl, and alicyclic of 4 to 6 carbon atoms, and a catalyst selected from the group consisting of copper oxides, transition elements and their oxides.

5. A process in accordance with claim 8 wherein the catalyst is selected from the group consisting of aluminum, copper, scandium, titanium, vanadium, chromium, manganese, iron, cobalt, nickel, yttrium, zirconium, niobium, molybdenum, technetium, ruthenium, rhodium, palladium, rhenium, tungsten, osmium, iridium, platinum, their oxides and mixtures thereof.

10. A process in accordance with claim 8 wherein the catalyst is copper.

11. A process in accordance with claim 8 wherein the catalyst is cuprous oxide.

12. A process of preparing primary and secondary esters of phosphoric acid comprising passing oxygen through a reaction mixture maintained at a temperature of at least about 65 degrees centigrade of a secondary ester of phosphorous acid of the formula

wherein R is selected from the group consisting of alkyl having from 1 to about 6 carbon atoms, halo-substituted alkyl having from 1 to about 6 carbon atoms, alkenyl having from 2 to about 6 carbon atoms, halo-substituted alkenyl having from 2 to about 6 carbon atoms, phenyl, alkylphenyl, halo-substituted phenyl and alkylphenyl and alicyclic having from 4 to about 8 carbon atoms and from 0.001 to about 0.1 mole per mole of phosphite of a catalyst selected from the group consisting of cuprous oxide, copper, vanadium pentoxide, cobalt trioxide and titanium dioxide and the oxygen being passed through the reaction mixture in an excess equal to from 1 to about 15 times the stoichiometric amount required.

13. A process of preparing primary and secondary esters of phosphoric acid comprising passing oxygen through a reaction mixture, maintained at a temperature of at least about 65 degrees centigrade, of phosphorus and a hydroxyl containing compound having the formula:

wherein R² is selected from the group consisting of phenyl, alkylphenyl phenylalkyl, alkyl, alkenyl, halo-substituted alkyl, halo-substituted alkenyl, and alicyclic having from 4 to about 6 carbon atoms, and from 0.001 to about 0.1 mole per mole of phosphorus of a catalyst selected from the group consisting of copper and cuprous oxide, the alcohol and phosphorus present in a ratio of from 1:1 to 5:1.

14. A process of preparing a primary ester of phosphoric acid comprising passing oxygen through a reaction mixture maintained at a temperature of at least about 65 degrees centigrade of a secondary ester of phosphorous acid of the formula

wherein R is selected from the group consisting of alkyl

5

10

having from 1 to about 6 carbon atoms, halo-substituted alkyl having from 1 to about 6 carbon atoms, alkenyl having from 2 to about 6 carbon atoms, halo-substituted alkenyl having from 2 to about 6 carbon atoms, phenyl alkylphenyl, halo-substituted phenyl and alkylphenyl and alicyclic having from 4 to about 8 carbon atoms and from 0.001 to about 0.1 mole per mole of phosphite of a catalyst selected from the group consisting of cuprous oxide, copper, vanadium pentoxide, cobalt trioxide and titanium dioxide and the oxygen being passed through the reaction mixture in an excess equal to from 1 to about 15 times the stoichiometric amount required.

15. A process of preparing a primary ester of phosphoric acid comprising passing oxygen through a reaction mixture, maintained at a temperature of at least about 65 degrees centigrade, of phosphorus and a hydroxyl containing compound having the formula:

20 wherein R² is selected from the group consisting of phenyl, alkylphenyl phenylalkyl, alkyl, alkenyl, halo-substituted alkyl, halo-substituted alkenyl, having from 2 to 6 carbon atoms, and alicyclic having from 4 to about 6 carbon atoms, and from 0.001 to about 0.1 mole per mole of phosphorus of a catalyst selected from the group consisting of copper and cuprous oxide, the alcohol and phosphorus present in a ratio of from 1:1 to 5:1.

UNITED STATES PATENT OFFICE
CERTIFICATE OF CORRECTION

Patent No. 3,333,030

July 25, 1967

Charles F. Baranauckas et al.

It is hereby certified that error appears in the above numbered patent requiring correction and that the said Letters Patent should read as corrected below.

Column 4, lines 65 to 68, the formula should appear as shown below instead of as in the patent:

column 8, line 4, for "phenyl" read -- phenyl, --.

Signed and sealed this 22nd day of April 1969.
